UNITED STATES PATENT OFFICE.

CHARLES J. VESLEY, OF PORTLAND, OREGON.

DISPLAY STAND.

Application filed May 18, 1927. Serial No. 192,362.

This invention is directed to a conveniently portable display stand designed primarily for cooperation with certain types of packages, with the packages more or less particularly constructed to permit their convenient application to and removal from the stand.

Certain packages of well known character, particularly those in bag-like form of 10 glassine or similar paper and containing potato chips, salted peanuts and the like, are, by reason of the irregular bulk of their contents and the character of the paper, difficult to arrange in piles or stacks for display and sale and are generally hard to arrange in convenient display and accessible form without requiring considerably more space than their nature warrants.

It is a particular object of the present invention to provide a readily portable stand 20 on which a comparatively large number of such packages may be conveniently arranged to support the packages in more or less bulk form in comparatively small space, 25 the packages being readily removed from the stand as required by sale or other disposition.

A further object is to provide a stand in 30 which the packages, while arranged in such perimposed relation, are nevertheless each readily visible to the purchaser, so that the contents of the packages, owing to the character of the paper employed, may be readily inspected to permit selection.

35 A further object is the provision of a stand of this character wholly and inexpensively constructed of wire rod or the like readily and inexpensively assembled, accommodating a comparatively large number 40 of packages in a comparatively small counter or shelf space.

The invention is illustrated in the accompanying drawings, in which:

Figure 1 is a perspective view of the improved stand, a number of packages being 45 shown thereon in dotted outline.

Figure 2 is a top plan view of the stand.

Figure 3 is a plan of one of the packages 50 constructed more particularly for cooperation with the stand.

The improved stand comprises a base 1 which, while preferably circular in outline, may if desired be of other form. The base includes a diametric base wire 2 secured at

its ends to the base and providing an anchorage for the upright or spindle 3 which at its lower end is anchored to the brace rod 2 in any appropriate manner and preferably extends upwardly at right angles to and axially of the base. The upright or spindle 3 may of course be of any desired height within the supporting limits of the base and its upper end is preferably pointed.

In order to provide a shed by which the lowermost packages will ordinarily be supported free of contact with the surface on which the base rests, and at the same time provide for further bracing the upright or spindle 3, there are provided additional brace rods indicated at 4 which extend preferably as a single brace from a point on the base to a corresponding diametric point on the base, the brace rods being inclined upwardly from their connection with and relative to the base to the spindle or upright, meeting the latter at a sufficient distance above the anchorage of the spindle or upright to the brace rod 2 to afford an effective bracing action of said spindle or upright. A plurality of such brace rods 4 are provided, four being shown, and these brace rods at their juncture with the spindle or upright 3 form in their crossing a central opening through which the spindle or upright 3 projects, it being understood that the brace rods 4 may be and preferably are secured to the spindle 3 at this point.

In Figure 3 is illustrated a package of the type for which the display stand is more particularly adapted, this package being in conventional form except that the margin indicated at 5, formed generally in such packages by interfolding the ends thereof, is for the purpose of use with the present stand provided with an eyelet 6 having an opening to readily cooperate with the spindle or upright 3. While preferring the use of such eyelet in order to facilitate applying and removing the packages without liability of tearing the envelope, it will of course be apparent that the stand may be used without such eyelet and the folded margin 5 of the package simply pierced by the spindle or upright 3 when applying the packages.

The display stand is designed to be used in stores where packages of the particular type referred to are sold and may be used

to support a number of such packages. It will be noted that the packages when provided with the eyelets are assembled in superimposed relation on the spindle or upright 5 right 3, the successive packages being vertically offset in circular form to accommodate a larger number of packages than would be otherwise possible. The inclined braces 4 serve as a shed to support the lowermost packages so that a considerable number 10 of packages may be arranged on the spindle or upright and the packages spread in substantially the same horizontal plane and radially disposed with respect to the spindle 15 or upright so that each successive layer of packages will include a comparatively large number of packages, permitting a display stand of comparatively short height to accommodate a comparatively large number of 20 packages. Where the packages are applied simply by piercing the fold 5, a particular package may be withdrawn from the display stand by a suitable pull sufficient to break through the fold. This is not a serious 25 inconvenience as such packages are usually opened and the contents consumed immediately, so that the initial breaking of the envelope is not important. It is preferred, however, that the packages be provided 30 with the eyelet in order to insure that their application on the spindle or upright may be at a proper point of the package

which would not necessarily follow where the fold was merely pierced.

What I claim to be new is:

35

1. A display stand comprising a ring-like base, a brace rod extending diametrically across the ring-like base, an article receiving spindle having its lower end secured to the intermediate portion of the brace rod 40 and extending upwardly therefrom, and a series of additional brace rods extending diametrically across the ring-like base, the free ends of the additional brace rods being secured to the ring-like base at diametrically 45 opposite points, the intermediate portions of the additional brace rods being bent and intersecting one another, the intersecting portions of the additional brace rods being secured to the spindle at a point above the 50 lower end thereof.

2. A display stand comprising an open base, a spindle rising from and supported by the base, and brace rods rising from the base and secured to the spindle at a point above the connection of the latter with the base, said brace rods being inclined from the spindle to the base and disposed radially of the spindle, whereby said brace rods form a shed to support a layer of packages 60 inclined with respect to the base and free of the surface on which the base rests.
